NOZZLE WITH RAM JET ACTION

Austin N. Stanton, Garland, Tex.

Application March 15, 1951, Serial No. 215,703

8 Claims. (Cl. 299—26)

1

This invention relates to nozzles and more particularly to nozzles for producing an intermittent high pressure flow of liquid through the nozzle when the nozzle is connected to a supply of liquid under comparatively low pressure.

In many applications e. g., washing automobiles, it is desirable to direct a stream of jet of water under high pressure against a surface which is incrusted with mud or other material in order to remove such material from the surface. Where a supply of water under high pressure is available, a flexible hose provided with an ordinary nozzle may be employed. Where the supply of water, however, is under low pressure, the stream of jet of water delivered by an ordinary nozzle will have a low velocity and will therefore be unable to wash away the incrustations of mud or other matter. It is desirable that, in such installation, the nozzle deliver a jet of water of high velocity, even though the supply of water is under comparatively low pressure.

Accordingly, it is an object of my invention to provide a new and improved nozzle.

It is another object of my invention to provide a new and improved nozzle which provides a high velocity jet of liquid when connected to a supply of liquid under low pressure.

Briefly stated, my new and improved nozzle comprises a cylindrical member one of whose ends is adapted to be connected to a flexible hose. The opposite end is externally threaded to engage an internally threaded cap provided with a central aperture and a plurality of outer apertures radially spaced about the central aperture. A nozzle member having a tapered forward extension is held for reciprocal movement between the cap and stops provided within the cylindrical member. The nozzle member is biased to an inward position with respect to the cylindrical member by a spring. In operation the liquid under low pressure flows through the cylindrical member, the nozzle member and the outer apertures until it attains a certain velocity. At that time the nozzle member is moved forwardly against the resistance of the spring by the force of flow of the liquid and closes the outer apertures. The liquid may then flow only through the nozzle member. The inertia of the liquid tends to maintain the same volume of water flowing through the cylindrical member and as a result, a jet of liquid of relatively high pressure is forced through the nozzle member. When the velocity of flow of the liquid is decreased, the force tending to move the nozzle member for-

2

ward is decreased and it moves back to its original position due to the force exerted by the spring. The outer apertures now being open, the velocity of the fluid flowing through the cylindrical member again increases until it exerts a sufficient force to move the nozzle member forwardly. The cycle of operation recurs as long as the liquid under pressure is supplied to the cylindrical member. In other embodiments of my invention, the nozzle member is maintained stationary but a valve member is provided which reciprocates in a similar manner to deliver an intermittent high pressure jet of liquid.

For a better understanding of my invention, reference may be had to the following description taken in connection with the accompanying drawing and its scope will be pointed out in the appended claims.

In the drawing, Figure 1 is a longitudinal sectional view of the assembled nozzle;

Figure 2 is a side plan view of the nozzle member;

Figure 3 is a perspective view of the cap;

Figure 4 is a longitudinal sectional view of a modified form of the device illustrated in Figures 1, 2, and 3; and,

Figure 5 is a longitudinal sectional view of still another modified form of the device illustrated in Figure 1.

Referring now to Figures 1, 2, and 3 of the drawing, a cylindrical member 10 preferably formed of metal is externally threaded on one end, as at 11, to engage and hold the internally threaded cap 12. The opposite end of cylindrical member 10 is enlarged as at 13. The enlarged part 13 of cylindrical member 10 is internally threaded to engage a fitting on the end of a hose. A washer 14 of rubber or other resilient substance may be provided to ensure a watertight joint between cylindrical member 10, and the hose fitting, not shown, to which it is to be attached.

Cap 12 is provided with a plurality of outer apertures 15 and a central aperture 16. A nozzle member 17 has an intermediate cylindrical portion 18 extending through the central aperture 16. The front end 19 of nozzle member 17 is tapered from intermediate portion 18 while the rear end is provided with a forwardly extending flange 20 which is connected to nozzle member 17 by an integral annular wall 21. Intermediate portion 18 is provided with a plurality of elongated circumferentially spaced apertures

22 whose front sides 23 extend forward and outwardly.

Flange 20 slidably abuts the inner surface of cylindrical member 10 and reciprocates between the forward end of cylindrical member 10 and the stops 24, at least a pair of which is rigidly secured to the inner surface of cylindrical member 10.

The edge of flange 20 may be provided with an annular gasket 25 which may be secured to flange 20 by any suitable means such as an adhesive. When nozzle member 17 is in its forward position, gasket 25 closes apertures 15 to prevent passage of liquid therethrough. A spring 26 bears against the cap 12 and against the annular wall 21 to bias nozzle member 17 toward stops 24.

In operation, the enlarged portion 13 of cylindrical member 10 is screwed on the fitting on one end of a hose whose other end is connected to a supply of liquid under comparatively low pressure, such as the water distribution system of a city. Water will therefore flow from the hose and through the cylindrical member 10 to nozzle member 17. When nozzle member 17 is in the position illustrated in Figure 1, water will flow through the elongated apertures 22 of nozzle member 17 and the outer apertures 15 of cap 12 as well as through the central opening 27 of nozzle member 17. Since a large volume of water will flow through apertures 15 and central opening 27 per unit of time, the velocity of the water flowing through cylindrical member 10 will increase until the force exerted on nozzle member 17 will overcome the rearwardly biasing force exerted by spring 26. Nozzle member 17 will then move forwardly. As soon as the nozzle member 17 begins to move forwardly, cap 12 will begin to close off apertures 22. Since the inertia of the water will tend to maintain its velocity of flow constant even though its freedom of flow has become restricted, relatively greater forces tending to move nozzle member 17 forward will be exerted by the water. This increase in the forces acting on nozzle member 17 causes it to move forward very quickly, once it starts its forward movement. When nozzle member 17 reaches its most forward position, gasket 25 closes outer apertures 15 so that the water can flow out only through central opening 27 of nozzle member 17. The velocity of the water in cylindrical member 10 imparts to it a momentum which tends to cause the water to continue to move forwardly at the same velocity even though it can now flow only through central opening 27. As a result, the water at nozzle member 17 is subjected to a relatively very high pressure which causes a jet of water under high pressure to be forced out through central opening 27. This jet will exist for only a short period of time since the velocity of the flowing water in cylindrical member 10 will soon decrease. When this occurs, the forces tending to maintain nozzle member 17 in its forward position will decrease and spring 26 will move nozzle member 17 to the position illustrated in the drawing. This will cause the apertures 15 to be opened again and the velocity of water flowing in cylindrical member 10 will again increase. This cycle of operation will recur continuously as long as water is supplied to cylindrical member 10 and an intermittent high pressure jet of water will issue from nozzle member 17.

The biasing force extended by spring 26 can be adjusted by rotating cap 12 to move its longitudinal position with respect to cylindrical member 10. A portion 28 of cap 12 is knurled to enable the cap 12 to be easily grasped even when wet.

Cylindrical member 10 is preferably formed of a non-elastic substance since otherwise the added pressure induced by the closing of apertures 15 would cause distention of cylindrical member 10 and a consequent loss of pressure at nozzle member 17. In some applications the flexible hose to which the nozzle is attached may also have to be non-elastic to prevent distention thereof.

Figure 4 illustrates a modified form of the nozzle shown in Figures 1 to 3. The nozzle member 29 is held stationary with respect to cylindrical member 10 by means of an annular internally threaded outer flange 30 which is connected to the tapered front end 31 of nozzle member 29 by an annulus 32 provided with a plurality of outer apertures 33. Nozzle member 29 is also provided with an inner flange 34 which is concentric with outer flange 30. A valve member 35 has an inner annular member 38. The inner annular member 36 is disposed slidably in flange 34 while the outer annular member 38 abuts the inner surface of cylindrical member 10 in sliding relation therewith and is disposed between stops 24 and annulus 32. The inner annular member 36 is provided with a plurality of apertures 39 while the outer annular member 38 has secured to it a resilient washer 40 which is adapted to seal outer apertures 33 when valve member 35 is moved toward nozzle member 29. A spring 41 biases valve member 35 toward stops 24.

The nozzle illustrated in Figure 5 is similar to that shown in Figure 4 except that the inner annular member 36 has been omitted and the inner flange 34 does not extend as far into cylindrical member 10. The mode of operation is exactly the same as that of the nozzle illustrated in Figure 4. Care must be taken to select a spring 41 whose resistance to compression does not increase appreciably as it is compressed by the forward movement of valve member 35.

The mode of operation of the device illustrated in Figure 4 is similar to that of the device illustrated in Figures 1 to 3. The valve member 35 will remain in the position shown in Figure 4 until the velocity of the water flowing through cylindrical member 10 increases to a value which causes the valve member 35 to move forwardly against the resistance of spring 41. This results in the closing of outer apertures 33 by washer 40 and a consequent increase in the pressure of the water at nozzle member 29. A high pressure jet of water will therefore be forced out the central aperture 42 of nozzle member 29. As soon as the increased pressure due to the cessation of flow of water through apertures 39 and 33 is relieved, valve member 35 is returned by spring 41 to the position illustrated in Figure 4.

While I have shown and described a preferred embodiment of my invention, it will be apparent that various changes and modifications can be made without departing from my invention and I, therefore, aim in the appended claims to cover all such changes and modifications as fall within the true spirit and scope of my invention.

What I claim as new and desire to secure by Letters Patent of the United States is:

1. In combination: a cylindrical member adapted to be connected to a source of fluid under pressure; a cap secured to one end of said cylindrical member, said cap being provided with a central aperture and a plurality of outer apertures; a nozzle member extending through said central aperture and having a flange disposed in said cylindrical member; and a spring oper-

atively associated with said cap and said nozzle member for biasing said flange to a position remote from said cap, said member being provided with circumferentially spaced apertures and a central opening, said circumferentially spaced apertures communicating with said outer apertures and the interior of said cylindrical member when said flange is in said position remote from said cap, said flange closing said outer apertures when said flange is moved toward said cap by the force exerted on the nozzle member by fluid flowing from said cylindrical member through said circumferentially spaced lateral apertures and said outer apertures and through said central aperture, said fluid flowing only through said central apertures of said nozzle member when said outer apertures are closed by said flange.

2. A nozzle comprising a cylindrical member adapted to be connected to a source of fluid; an apertured member rigidly secured to one end of said cylindrical member and provided with a plurality of outer apertures and a central aperture; a movable hollow member mounted for reciprocal movement within said cylindrical member adjacent said apertured member, said movable member being adapted to close said outer apertures when moved toward said apertured member by the fluid flowing through said cylindrical member, fluid flowing from said cylindrical member through said movable member and through said outer apertures and said central aperture when said outer apertures are not closed by said movable member, fluid flowing from said cylindrical member through said movable member and only through said central aperture when said outer apertures are closed by said movable member; and a resilient member operatively associated with said movable member for biasing said movable member away from said apertured member.

3. A nozzle comprising a cylindrical member; an apertured member rigidly secured to one end of said cylindrical member and provided with a plurality of outer apertures and a central aperture, said apertures communicating with the interior of said cylindrical member; a movable hollow member mounted for reciprocal movement within said cylindrical member, said movable member closing said outer apertures when moved toward said apertured member by the fluid flowing through said cylindrical member from said source, fluid flowing from said cylindrical member through said movable member and through said outer apertures and said central aperture when said movable member is positioned remote from said apertured member, fluid flowing from said cylindrical member and only through said central aperture when said outer apertures are closed by said movable member; and a resilient member operatively associated with said movable member for biasing said movable member away from said apertured member.

4. A nozzle comprising a cylindrical member adapted to be connected to a source of fluid under pressure; a nozzle member rigidly secured to one end of said cylindrical member, said nozzle member being provided with a central aperture and a plurality of outer apertures disposed about said central aperture; a valve member slidably disposed within said cylindrical member for closing said outer apertures to interrupt a portion of the flow of fluid from said cylindrical member through said nozzle member

when the fluid flowing through said cylindrical member attains a predetermined velocity; and a resilient member between said nozzle member and said valve member for biasing said valve member away from said nozzle member when the velocity of the fluid flowing through said cylindrical member is less than the predetermined velocity.

5. A nozzle comprising a cylindrical member adapted to be connected to a source of fluid under pressure; a nozzle member rigidly secured to one end of said cylindrical member, said nozzle member being provided with a central aperture and a plurality of outer apertures disposed about said central aperture; a valve member slidably disposed in said cylindrical member and having an outer annular member, an inner annular member, and an annular member perpendicular to and connecting said outer and inner annular members, said outer annular member closing said outer apertures when said valve member is moved toward said nozzle member by the force exerted on said valve member by fluid flowing from said cylindrical member through said valve member and through said outer apertures and said central aperture of said nozzle member to interrupt a portion of the flow and produce a spurt of fluid through said central aperture; and a resilient member between said nozzle member and said valve member for biasing said valve member away from said nozzle member.

6. A nozzle comprising a cylindrical member having one end connected to a source of fluid under pressure; a nozzle member rigidly secured to the other end of said cylindrical member, said nozzle member being provided with a central aperture and a plurality of outer apertures disposed about said central aperture; a hollow valve member slidably disposed in said cylindrical member and having an outer annular member, an inner annular member and an annular member perpendicular to and connecting said outer and inner annular members, said outer annular member closing said outer apertures when said valve member is moved toward said nozzle member; said inner annular member being provided with a plurality of apertures which communicate with said outer apertures when said valve member is in a position remote from said nozzle member, said nozzle member comprising an inner annular flange disposed in telescoped relation with said inner annular member; and a resilient member between said valve member and said nozzle member for biasing said valve member away from said nozzle member, said valve member being moved toward said nozzle member against the resistance of said resilient member when the fluid flowing from one end of said cylindrical member to the other exceeds a predetermined velocity by the force exerted on said valve member by said fluid, fluid flowing from said cylindrical member through the apertures in said inner annular member and said outer apertures and through said central aperture when said valve member is remote from said nozzle member, fluid flowing from said cylindrical member through said valve member and said central aperture when said valve member is moved toward said nozzle member to close said outer apertures.

7. Apparatus for delivering an intermittently spouting jet of fluid comprising a cylindrical member having a fluid inlet for feeding it with fluid under pressure and a fluid outlet; a nozzle

member closing said fluid outlet and having a main central aperture and a plurality of outer apertures; a valve member in said cylindrical member movable toward said nozzle member for closing said outer apertures; and a resilient member biasing said valve member normally to maintain said valve member remote from said nozzle member, said valve member being moved toward said nozzle member to close said outer apertures by the forces exerted by the fluid flowing through said cylindrical member when the velocity of said fluid exceeds a predetermined value, said valve member moving away from said nozzle member when the velocity of the fluid flowing through said cylindrical member falls below said predetermined value.

8. Apparatus for delivering an intermittently spurting jet of fluid comprising a cylindrical member having a fluid inlet for feeding it with fluid under pressure and a fluid outlet; an apertured member closing said fluid outlet and provided with a plurality of outer apertures and a central aperture; a movable member mounted for reciprocal movement within said cylindrical member adjacent said apertured member for

10
5

movement toward said apertured member for closing said outer aperture; and a resilient member normally to maintain said movable member remote from said apertured member, said movable member being moved toward said apertured member to close said outer apertures by the forces exerted by the fluid flowing through said cylindrical member when the velocity of said fluid exceeds a predetermined value, said resilient member moving said valve member away from said apertured member when the velocity of the fluid flowing through said cylindrical member falls below said predetermined value.
